United States Patent Office.

JOHN J. PELLETT, OF OCONOMOWOC, WISCONSIN.

Letters Patent No. 77,088, dated April 21, 1868.

IMPROVEMENT IN GATES.

The Schedule referred to in these Letters Patent and making part of the same.

TO ALL WHOM IT MAY CONCERN:

Be it known that I, JOHN J. PELLETT, of Oconomowoc, in the county of Waukesha, and State of Wisconsin, have invented a new and improved Gate; and I do hereby declare that the following is a full, clear, and exact description of the construction and operation of the same, reference being had to the annexed drawings, making a part of this specification, in which—

Figure 1 is a side elevation.

Figure 2 is a cross-section.

This invention relates to the class of farm-gates which are expanded and contracted longitudinally in order to close or open them, by means of the device known as "Jacob's Ladder," and consists in enclosing said ladder between the bars of a sliding frame, by which the gate is greatly strengthened, and at the same time rendered more beautiful in appearance.

In the drawings, *a a* represent the Jacob's ladder; *B*, the post against which the gate closes; *C*, the post to which it is hung; *D D*, guide-posts, of any suitable height; *E E*, posts that support the shaft by which the gate is opened or closed; *F*, the shaft referred to, having a pulley, *G*, and an arm, *H*, attached to it, and *I* a cord, passing once or more around the pulley or wheel *G*, to one point on the rim of which it is fastened to prevent slipping, and having its ends attached to the extremities of the gate. By turning the crank in one direction, the cord *I* draws the gate to the right, as seen in fig. 1, and leaves the way open; and by turning the crank in the opposite direction, the gate is forced to the left and closed. The arms *H H* are connected together by a rod, *h*, and are attached to the shaft by a loose joint, which permits them to be rocked to the right or left, as seen by the black and red lines in fig. 2. By this means the gate may be securely locked when closed, it being only necessary to bring one of the arms *H H* behind and in contact with a pin or projection, *h'*, fixed to one of the posts *E E*. The projection *h'* may be in the form of a hook, if desired, whereby it will more securely hold the arm, and the side opposite to the concave may be bevelled or inclined to facilitate the locking of the device. It will only be necessary to provide one locking-pin or hook, as the arms can both be operated from either side of the gate by means of the connecting-rod *h*.

The bar *a*, which at its lower end is pivoted to the post *C*, is attached at said pivot by a fixed hinge, *k*. The bar in connection with it, that is pivoted at its top to the same post, is hinged to said post by means of a pivoted arm, *m*, one end of which is attached to the post, and the other to the bar *a*, as seen in fig. 1. As the Jacob's ladder is expanded or contracted in length, the position of the two bars connected to post *C* will be changed, sometimes being more and sometimes less vertical, and the arm *m* will rise and fall, accommodating itself to this change of position.

The main feature of the invention, however, consists in providing an enclosing-frame, composed of the upright standards *S S'*, the latter outside of the post *C*, and the former inside of the post *B*, united together by longitudinal rails *T T' T'*, which extend from standard to standard, on both sides of the "ladder," enclosing it between them. A pin, *T*, passes through the middle rail *T'*, and the two bars *a a*, that stand adjacent to the standard *S*, that being the only point at which the ladder is connected with the enclosing-frame. The ends of the cord *I* are attached to the standards *S S'*, and slide the enclosing-frame back and forth, the "ladder" inside of the frame contracting or expanding in proportion to the movement of the frame.

I am aware that gates have for many years been constructed on the Jacob's ladder principle, but without the enclosing-frame. They have therefore been weak and easily racked out of position, besides being liable to get out of repair. By the use of the frame, however, the gate is greatly strengthened and supported, besides being rendered more agreeable to the eye. I do not broadly claim the use of such ladder; but

What I do claim as my invention, and desire to secure by Letters Patent, is—

1. The combination of the pivoted bars *a a* with the enclosing-frame *S S' T T' T'*, when operating substantially as and for the purpose set forth.
2. The combination of the arms *H H*, connecting-rod *h*, and locking-pin *h'*, when used in connection with a sliding gate, as above described, and with the wheel and cord for opening and shutting it, as a device for securely locking said gate, in the manner described.

To the above specification of my improvement, I have signed my hand, this eighteenth day of February, 1868.

JOHN J. PELLETT.
